Primary Examiner — Susan Krakower*Assistant Examiner* — Lisa A Grabenstetter(74) *Attorney, Agent, or Firm* — Finch & Maloney PLLC**(57) CLAIM**

The ornamental design for an upright brush, as shown and described.

DESCRIPTION

FIG. 1 is a perspective view of a first embodiment of an upright brush showing our new design;

FIG. 2 is a front view thereof;

FIG. 3 is back view thereof;

FIG. 4 is a left-side elevational view thereof, the right-side elevational view being a mirror image thereof;

FIG. 5 is a top plan view thereof;

FIG. 6 is a bottom plan view thereof;

FIG. 7 is a perspective view of a second embodiment of an upright brush showing our new design;

FIG. 8 is a front view thereof;

FIG. 9 is back view thereof;

FIG. 10 is a left-side elevational view thereof, the right-side elevational view being a mirror image thereof;

FIG. 11 is a top plan view thereof; and,

FIG. 12 is a bottom plan view thereof.

The broken line portions of FIGS. 6 and 12 show unclaimed subject matter only and form no part of the claimed design.

1 Claim, 10 Drawing Sheets---
